ROTARY CIGARETTE CATCHER

George W. Gwinn, Hewlett, N. Y., assignor to
American Machine & Foundry Company, a cor-
poration of New Jersey

Application June 22, 1935, Serial No. 27,923

21 Claims. (Cl. 198—25)

This invention relates to improvements in cigarette catchers for continuous-rod cigarette machines, its main object being to provide a simple device for receiving the rapidly moving cigarettes issuing lengthwise from the cigarette machine cutoff wherein they are severed from the cigarette rod and displacing them transversely from the path of the cigarette rod.

This object, in the present invention, may be achieved by a rotary member of helical or other suitable configuration, such as a rotating worm set at an angle to the collector belt and having a pitch greater than the thickness of a cigarette, the cigarettes being delivered into its spiral thread 5 issuing lengthwise from the cigarette machine cutoff wherein they are severed from the cigarette rod and displacing them transversely from the path of the cigarette rod.

10 by a segmental wheel revolving at a circumferential speed in excess of the linear speed of the cigarettes delivered from the cutoff so as to separate them lengthwise. To keep them separated while passing into the worm, the segmental wheel 15 may deliver them lengthwise on to a narrow endless separating belt running at a linear speed equal to or greater than the circumferential speed of the segmental wheel, this belt supporting the cigarette while advancing it into the 20 thread of the worm. Furthermore, the segmental wheel may be omitted and the cigarettes may be separated lengthwise by the action of the separating belt alone. After the cigarette has been 25 displaced sidewise by the turning of the worm through one revolution, it crosses an endless reversing belt running parallel with, but in the opposite direction to, the separating belt, this second belt retarding the forward speed of the cigarette lengthwise and finally causing it to 30 travel lengthwise against a stop while still being moved sideways by the thread of the worm. Upon 35 leaving the worm, the then stationary cigarette is pushed by the succeeding cigarettes on to a collector belt which runs transversely of the separating and reversing belts.

The worm may be single or double-threaded, the latter having the advantage that due to its greater pitch the worm may be rotated at a lower speed and yet displace each cigarette sidewise 40 out of the way of the succeeding cigarette. Furthermore, the lead of the worm may be gradated from a large pitch at the receiving end to a smaller lead at the delivery end of the worm, the limit of the delivery pitch being the diameter of a 45 cigarette, in which case the cigarettes issuing from the worm would be in contact. Moreover, the helical member may constitute only a single turn of a helix, or a fraction thereof; nor should it be understood that the invention is limited to 50 a member of helical configuration, as various con-

figurations are suitable for the purpose of the present invention.

With this and other objects not specifically mentioned in view, the invention consists in certain constructions and combinations hereinafter 5 fully described and then specifically set forth in the claims hereunto appended.

In the accompanying drawing which forms a part of this specification and in which like characters of reference indicate the same or like 10 parts:

Fig. 1 is a top view of the improved cigarette catcher;

Fig. 2 is a front elevation of the same; and

Fig. 3 is a partial side elevation thereof on line 15 3—3 of Fig. 1.

In carrying the invention into effect there is provided in a cigarette catcher receiving cigarettes severed from a cigarette rod in a cigarette machine, means for successively advancing the 20 severed cigarettes lengthwise to separate the same and displacing them transversely from the path of the cigarette rod. In the best constructions contemplated this means comprises a rotating worm arranged to receive in its thread the 25 line of cigarettes issuing from the cigarette machine cutoff and successively displace them sidewise, and the cigarettes may be first accelerated 30 to separate them lengthwise. The improved cigarette collector may be widely varied within the 35 scope of the claims, for the particular construction selected to illustrate the invention is but one of many possible concrete embodiments of the same. The invention, therefore, is not to be restricted to the precise details of the structure 40 shown and described.

Referring to Figs. 1 to 3 of the drawing, the line of cigarettes C issuing from the cutoff of a cigarette machine (not shown) travels lengthwise on a grooved plate 5 at one side of the driving pulley 6 of a collector belt 7 running at right angles to the cigarette rod from which the cigarettes are severed in the cutoff. The shaft 8 of pulley 6 is driven from the cigarette machine, and the upper run of the belt 7 is supported by 45 a plate 9 and has side guides 10 and 11.

To transfer the cigarettes sidewise to the belt 7, a worm 12 is mounted on a shaft 13 which is supported obliquely to the belt 7 by a frame 14 so that the groove of its spiral thread, at the bottom 50 of the worm, will extend in the direction of the oncoming cigarettes to admit them lengthwise and follow their lengthwise movement while displacing them sidewise in parallelism with the cigarette rod. It may be noted that the cig- 55

5   aretes are thus moved in an angular path during their lateral displacement. The ends of the cigarettes C on plate 5 touch one another, hence when transferring them one by one to the trans-
 10   verse collector belt 7 their ends would rub against each other and be damaged unless they were first longitudinally separated sufficiently to allow the leading cigarette to be moved out of the way side-
 15   wise before the next cigarette reaches the worm.
 10   For this purpose a segmental wheel 15 is provided having on its raised segment a circumferential speed greater than the forward speed of the cigarettes on plate 5, the raised segment of the said wheel being preferably grooved to provide out-
 15   standing flanges which securely guide the cigarettes into the thread of the worm 12. The shaft 28 of wheel 15 is also supported in frame 14 and driven from the cigarette machine. It should be understood however that the worm 12
 20   may be disposed at right angles to the cigarette rod, whence the cigarettes will be delivered askew to the collector belt 7; and that the angle of the belt with respect to the cigarette rod could also be varied to receive the cigarettes squarely if the worm were arranged at right angles to the cigarette rod and thus acted to deliver them askew.

A traveling surface such as a narrow endless belt 16 may be provided upon which each cigarette is delivered by the wheel 15 and upon which it rests during the first revolution of the worm, the shafts 17 and 18 of the pulleys 19 and 20 of this separating belt being supported in frame 14 and one of these shafts being driven from the cigarette machine in the forward direction at a speed sufficient to keep the cigarettes separated. After one revolution of the worm, when the cigarette C' (Fig. 1) has been displaced sidewise out of the way of the following cigarette, the continued rotation of the worm displaces the cigarette C' on to a second endless belt 21 running over pulleys 22 and 23 on shafts 24 and 25 and driven from the cigarette machine at low speed in the opposite direction to belt 16. The reversing belt 21 gradually stops the forward lengthwise motion of the cigarette C' and finally moves it backward slowly against a stop 26 which may be an extension of the rear guide 11 of collector belt 7.

To support the cigarettes while being transferred by the worm from belt 16 to belt 21 and from belt 21 to belt 7, a plate 27 is provided which bridges the gaps between these belts. To quickly displace the cigarettes sidewise immediately after they enter the worm and yet avoid too large a separation between the cigarettes leaving the same, the pitch of the spiral-thread of the worm 12 is made greatest at the receiving end and gradually decreases towards the delivery end of the worm. In this connection it may be noted that the thread of the worm straddles the cigarettes during their lateral displacement and thus controls the momentum thereof, and that the shaft 13 thereof is driven from the cigarette machine drive in properly timed relation to the cigarette machine cutoff.

65   What is claimed is:

1. In a cigarette catcher, the combination with mechanism for receiving and guiding a line of cigarettes severed from a cigarette rod in a cigarette machine cutoff, of a single rotary means having its axis of rotation transverse to the cigarette rod for moving the severed cigarettes transversely from the path of the cigarette rod, said means having opposed spiral faces straddling the cigarette while moving it laterally so as to control the momentum of its transverse movement.

2. In a cigarette catcher, the combination with mechanism for receiving and guiding a line of cigarettes severed from a cigarette rod in a cigarette machine cutoff, of a rotary member having its axis transverse of the path of the cigarette 5 rod for transferring cigarettes transversely from the path of the rod substantially axially of said member, said member having a groove into which the cigarettes enter to be transferred.

3. In a cigarette catcher, the combination with mechanism for receiving and guiding cigarettes severed from a cigarette rod in a cigarette machine cutoff, of rotary means having a plurality of spiral cigarette engaging faces for engaging and moving a plurality of cigarettes transversely 15 from the path of the cigarette rod, said means moving on an axis transverse of the path of the cigarette rod, and the faces thereof which move the cigarettes being substantially parallel with the length of each cigarette during said engagement and transverse movement, said faces being spaced axially along said member to simultaneously displace a plurality of cigarettes laterally and parallel to the path of said rod during the rotation of said means.

4. In a cigarette catcher, the combination with mechanism for receiving and guiding a line of cigarettes severed from a cigarette rod in a cigarette machine cutoff, of means for successively advancing the severed cigarettes lengthwise to 30 establish a gap between the leading cigarette in said line and the following cigarette in the path of the cigarette rod, a rotary member for displacing said leading cigarette transversely from the path of the rod, a stop and a member having 35 a traveling surface for retarding and finally reversing the lengthwise movement of said leading cigarette after it is out of the path of the rod to advance it against said stop at a speed less than that of the cigarette rod.

5. In a cigarette catcher, the combination with mechanism for receiving and guiding a line of cigarettes severed from a cigarette rod in a cigarette machine cutoff, of means for successively displacing the severed cigarettes transversely 45 from the path of the cigarette rod, and a traveling member having a surface moving in a direction parallel with but opposite to the direction of movement of said rod and contacting with the cigarettes while they are being displaced from the path of the cigarette rod for retarding and finally reversing the lengthwise movement of the cigarettes to halt the same.

6. In a cigarette catcher, the combination with mechanism for receiving and guiding a line of 55 cigarettes severed from a cigarette rod in a cigarette machine cutoff, of a rotary member having its axis transverse to the movement of the cigarette rod for laterally moving the cigarettes successively out of the path of the oncoming rod, 60 said member having a flange of progressively decreasing pitch arranged to successively receive each cigarette and move it transversely, first at high speed to clear the following cigarette and then at a low speed while disengaging it.

7. In a cigarette catcher, the combination with mechanism for receiving and guiding a line of cigarettes severed from a cigarette rod in a cigarette machine cutoff, of a rotary member arranged on a horizontal axis extending transversely of and located above the line of cigarettes, 70 said member having a spiral cigarette engaging vane extending axially therealong for displacing cigarettes sidewise and parallel to said rod, said vane being constructed with a plurality of turns 75

for also engaging with previously displaced cigarettes for imparting thereto an additional sidewise movement.

8. In a cigarette catcher for receiving cigarettes endwise from a cigarette machine cutoff and collecting them sidewise in a row, the combination with a traveling collector belt extending transversely with respect to the line of cigarettes issuing from the cigarette machine cutoff, of a rotating worm arranged to receive in its thread the cigarettes issuing from the cigarette machine cutoff and deliver them sidewise to said collector belt.

9. In a cigarette catcher for receiving cigarettes endwise from a cigarette machine cutoff and collecting them sidewise in a row, the combination with a traveling collector belt extending transversely with respect to the line of cigarettes issuing from the cigarette machine cutoff, of a rotating worm arranged to receive in its thread the cigarettes issuing endwise from the cigarette machine cutoff and deliver them sidewise to said collector belt, the thread on said worm having a progressively decreasing pitch in order to displace the cigarettes sidewise at a gradually decreasing speed.

10. In a cigarette catcher for receiving cigarettes endwise from a cigarette machine cutoff and collecting them sidewise in a row, the combination with a traveling collector belt extending transversely with respect to the line of cigarettes issuing from the cigarette machine cutoff, of a device for accelerating the cigarettes delivered from the cigarette machine cutoff, to separate them lengthwise, and a rotating worm arranged to receive the cigarettes in its thread from said device after they have been separated lengthwise and deliver them sidewise to said collector belt.

11. In a cigarette catcher for receiving cigarettes endwise from a cigarette machine cutoff and collecting them sidewise in a row, the combination with a traveling collector belt extending transversely with respect to the line of cigarettes issuing from the cigarette machine cutoff, of a device for accelerating the cigarettes delivered from the cigarette machine cutoff, to separate them lengthwise, and a rotating worm arranged to receive the cigarettes in its thread from said device after they have been separated lengthwise and deliver them sidewise to said collector belt, said device including a rotating wheel having a raised segment for engaging each cigarette successively and accelerating it to separate it from the following cigarette, said raised segment being provided with outstanding flanges which serve to guide the cigarettes while they are being accelerated.

12. In a cigarette catcher for receiving cigarettes endwise from a cigarette machine cutoff and collecting them sidewise in a row, the combination with a traveling collector belt extending transversely with respect to the line of cigarettes issuing from the cigarette machine cutoff, of a device for accelerating the cigarettes delivered from the cigarette machine cutoff to separate them lengthwise, and a rotating worm arranged to receive the cigarettes in its thread from said device after they have been separated lengthwise and deliver them sidewise to said collector belt, and a traveling belt for advancing the separated cigarettes lengthwise into the thread of said worm at the speed to which they have been accelerated.

13. In a cigarette catcher for receiving cigarettes endwise from a cigarette machine cutoff and collecting them sidewise in a row, the com-

bination with a traveling collector belt extending transversely with respect to the line of cigarettes issuing from the cigarette machine cutoff, of a device for accelerating the cigarettes delivered from the cigarette machine cutoff to separate them lengthwise, and a rotating worm arranged to receive the cigarettes in its thread from said device after they have been separated lengthwise and deliver them sidewise to said collector belt, a stop extending along said member, and a traveling reversing belt underlying the cigarettes being displaced sidewise by said worm and acting to advance them lengthwise against said stop.

14. In a cigarette catcher for receiving cigarettes endwise from a cigarette machine cutoff and collecting them sidewise in a row, the combination with a traveling collector belt extending transversely with respect to the line of cigarettes issuing from the cigarette machine cutoff, of a device for accelerating the cigarettes delivered from the cigarette machine cutoff to separate them lengthwise, and a rotating worm arranged to receive the cigarettes in its thread from said device after they have been separated lengthwise and deliver them sidewise to said collector belt, the thread on said worm having a gradually decreasing pitch to displace the cigarettes sidewise at a gradually decreasing speed.

15. Means for accelerating cigarettes delivered from a cigarette machine cutoff, to separate them lengthwise, comprising a rotating wheel having a raised segment for engaging each cigarette successively and accelerating it to separate it from the following cigarette, said raised segment being provided with outstanding flanges which serve to guide the cigarettes while they are being accelerated.

16. In a cigarette catcher, the combination with mechanism for receiving and guiding a line of cigarettes severed from a cigarette rod in a cigarette machine cutoff, of rotary means having its axis of rotation transverse to the cigarette rod for moving the severed cigarettes laterally from the path of the cigarette rod, said means having opposed faces straddling each cigarette while moving it laterally and substantially parallel to the direction of movement of said rod so as to control the momentum of its transverse movement, and means for stopping the endwise movement of the transversely moving cigarettes.

17. In a cigarette catcher, the combination with mechanism for receiving and guiding a line of cigarettes severed from a cigarette rod in a cigarette machine cutoff, of rotary helical means having its axis of rotation transverse to the cigarette rod for moving the severed cigarettes transversely from the path of the cigarette rod, said means straddling the cigarette while moving it so as to control the momentum of its transverse movement.

18. In a cigarette catcher, the combination with mechanism for receiving and guiding a line of cigarettes severed from a cigarette rod in a cigarette machine cutoff lengthwise on a support, of a grooved member positioned above the rod and on an axis transverse to the path of movement of said rod with the groove of said member forming faces spaced to admit cigarettes therebetween, said faces being arranged to move in the general direction of movement of said line of cigarettes while displacing cigarettes laterally from said line, a cigarette receiving device located adjacent said member, and means for imparting motion to said member to cause said faces to move cigarettes from said line to said device.

19. In a cigarette catcher, the combination with mechanism for receiving and guiding a line of cigarettes severed from a cigarette rod in a cigarette machine cutoff, of rotary means mounted upon a substantially horizontal shaft having its axis of rotation transverse to the cigarette rod for moving the severed cigarettes transversely from the path of the cigarette rod, said means having spaced surfaces contacting opposite sides of a cigarette while moving it so as to control the momentum of its transverse movement.

20. In a cigarette catcher, the combination with mechanism for receiving and guiding cigarettes severed from a cigarette rod in a cigarette machine cutoff, of a receiving member onto which said cigarettes are delivered, rotary means provided with spiral cigarette engaging and displacing faces positioned axially along said means, said faces being constructed and arranged to displace cigarettes laterally from the cigarette rod

and also move previously displaced cigarettes onto said member, said means moving on an axis transverse of the path of the cigarette rod, and the faces thereof which move the cigarettes being substantially parallel with the length of the cigarettes during the engagement and movement.

21. In a cigarette catcher, the combination with mechanism for receiving and guiding a line of cigarettes severed from a rod in a cigarette machine cutoff, of a rotary member having its axis substantially transverse to the path of movement of said rod, said member having a spiral vane comprising a plurality of turns extending axially thereof for moving cigarettes laterally from said rod, said vane having a decreasing pitch so constructed and arranged that cigarettes are moved at a high rate of speed from said rod and then at a lower rate of speed when disengaged by said vane.
